UNITED STATES PATENT OFFICE.

STEPHEN A. KOST, OF BUFFALO, NEW YORK, ASSIGNOR TO EXCELLO MANUFACTURING COMPANY, OF CLEVELAND, OHIO, A CORPORATION OF OHIO.

GLAZING APPARATUS.

1,363,602.

Specification of Letters Patent. Patented Dec. 28, 1920.

Application filed July 18, 1919. Serial No. 311,749.

To all whom it may concern:

Be it known that I, STEPHEN A. Kost, a citizen of the United States, residing in Buffalo, in the county of Erie and State of New York, have invented new and useful Improvements in Glazing Apparatus, of which the following is a specification.

This invention relates to an apparatus which is more particularly designed for applying glazing material to a window sash for securing glass panes thereon, although the device may also be used for analogous purposes.

The object of this invention is to provide a simple and inexpensive means for this purpose which can be readily operated by the use of one hand, which can be readily filled and conveniently operated for discharging the entire contents of the device upon the surface intended to receive the same, and which can be easily dismembered for inspection and cleaning.

In the accompanying drawings:

Figure 1 is a longitudinal section of my improved glazing apparatus showing the plunger in the rearmost position within the barrel and the valve at the front or outlet end of the barrel closed. Fig. 2 is a side elevation of the same taken at right angles to Fig. 1. Fig. 3 is a rear end view of the apparatus shown in Figs. 1 and 2. Fig. 4 is a side elevation, partly in section, of the glazing apparatus showing a modified form of my invention. Fig. 5 is a rear end view of the same. Fig. 6 is a side elevation, partly in section, showing another modification of my improvement. Fig. 7 is a rear end view of the same.

Similar characters of reference refer to like parts throughout the several views.

The form of glazing apparatus shown in Figs. 1-3 is constructed as follows:

10 represents the barrel or cylinder of the apparatus which is adapted to contain the supply of glazing material or other substance which is to be deposited, this material being usually of semi-fluid character. At its front end this barrel is provided with a reduced delivery nozzle 11 forming an outlet through which the material is entirely discharged from the barrel. This outlet may be controlled by a valve of any suitable construction, that shown in the drawings being preferred and constructed as follows:

12 represents a valve rod or stem which

slides transversely in a guide opening which is formed in the nozzle so as to intersect the outlet therein and which is provided with a port 13 so that upon moving this valve stem inwardly the port 13 will be caused to register with the outlet of the nozzle and permit the material to escape from the barrel while upon moving this valve stem outwardly so that its support is out of register with the outlet passage in the nozzle, as shown by full lines in Fig. 1, then the escape of material from the barrel is arrested. The inward or opening movement of the valve stem is preferably effected by means of a hand lever 15 which is pivoted at its front end by means of a pin 19 on an adjacent part of the nozzle 11, while its intermediate part is provided with a longitudinal slot 18 which receives a pin 17 on the outer end of the valve stem. The outward movement of the valve stem is preferably effected by means of a spring 16 surrounding the valve stem and bearing at its opposite ends against the inner side of the hand lever 15 and adjacent outer surface of the discharge nozzle. The outward motion of the valve stem under the action of the spring 16 is preferably limited by a stop device consisting of a screw nut 14 mounted on that end of the valve stem which projects from that side of the nozzle opposite to that which is engaged by the spring 16, said stop nut being adapted to engage the adjacent surface of the nozzle when the valve is in its closed position.

Movable lengthwise within the barrel is a plunger or piston, which during its forward movement, is adapted to discharge the material from the barrel through the front outlet of the same when it is open. This plunger may be variously constructed, but in the preferred form shown in the drawings the same comprises a cup shaped packing 20 of leather or other suitable material which engages its peripheral portion with the front end of the barrel and two metal retaining plates or disks 21, 22 engaging with the front and rear sides of this packing.

23 represents a longitudinal shifting rod which is secured at its front end to the central part of the plunger while its rear part is provided with an external screw thread. The connection between this shifting rod and the piston may be produced in various ways, for instance, by providing the front end of this rod with a reduced portion which

passes through corresponding openings in the packing and plates of the plunger and forms a forwardly facing shoulder on this rod which engages with the rear plate 22, 5 and a screw nut 24 is applied to the front end of this rod and engages with the front plunger plate 21.

Upon the screw threaded rear part of this shifting rod is mounted a screw nut 25 which 10 may be turned by any suitable means for moving this nut forwardly or backwardly on the shifting rod. 26 represents a spring of helical form which surrounds the rear part of the shifting rod and bears at its front end 15 against the rear side of the screw nut 25.

The outer end of the spring 26 bears against the cross bar 28 of the yoke, which latter is provided on its central part with an opening 27 which receives the rear part of 20 the shifting rod while its opposite ends are provided with forwardly projecting arms 29 which are detachably and pivotally connected with the rear part of the barrel by providing the opposite sides of the latter 25 with coupling pins 30 and providing the front ends of the yoke arms 29 with L-shaped slots 31 so that the same form hooks which engage with the coupling pins 30.

Assuming that the barrel has been filled 30 with material and the valve which controls the outlet of the same is closed and the plunger is in its rearmost position and the spring 26 has been placed under tension by turning the screw nut 25 so that it is moved backwardly on the shifting rod, a discharge 35 of the material from the barrel will be effected immediately upon opening the valve stem 12 by the hand lever 15 by reason of the forward movement of the plunger which 40 is produced at this time by the resilience of the spring 26. This forward motion of the plunger continues until the resilience of the spring 26 has been exhausted. In order to 45 again restore the automatic ejection of the material in the barrel upon opening the valve 12, the spring 26 is again placed under tension by screwing the nut 25 backwardly on the shifting rod 23 until the spring 26 has been again compressed the 50 desired extent. When, thereafter, the valve 12 is again opened the discharge of the material from the apparatus will be again resumed by the pressure of the spring 26 which is transmitted to the plunger through 55 the medium of the shifting rod and screw nut, this resetting of the spring being repeated as often as required for fully discharging the contents from the barrel.

For the purpose of again refilling the barrel 60 with a new charge of material, the plunger is removed from the rear end thereof so as to permit this charge to be introduced into the barrel at this end. The withdrawal of the plunger for this purpose may be 65 effected in a variety of ways, for instance,

the side bars or arms 29 of the yoke may be detached from the pins 30 and then the plunger and associated parts may be removed entirely from the barrel. After the barrel has been filled, these parts may be 70 again restored in like manner. If desired the screw nut 25 may be first run forwardly its fullest extent on the shifting rod 23 and the latter moved rearwardly to such an extent that the plunger is withdrawn from the 75 rear end of the barrel after which the yoke together with the shifting rod, plunger and associated parts mounted thereon may be swung laterally so as to clear the rear end of the barrel from obstructions and permit 80 the same to be conveniently refilled with material. After this, the yoke may be again swung into its normal position and the plunger inserted in the rear end of the barrel preparatory to placing the spring 26 under 85 pressure and resuming using the material like that previously described.

Instead of employing the spring means shown in Figs. 1, 2, and 3 for automatically propelling the plunger forwardly when the 90 valve in the outlet of the barrel is open, substantially the same result may be obtained by means employed in the construction shown in Figs. 4 and 5, which means consist of a flat O-spring 34 secured at its opposite 95 ends on opposite sides of the barrel at the rear end thereof, while its central part bears against the rear side of a screw nut 32 arranged on the threaded shifting rod 23 and is provided with an opening 33 which receives said shifting rod.

By screwing the nut 32 backwardly on the shifting rod 23 the O-spring 34 is placed under pressure by changing its form from that shown by full lines in Fig. 4 to that 105 shown by dotted lines in the same figure, thereby causing this spring to automatically advance the plunger and eject the material from the outlet of the barrel when the valve 12 is open.

Another construction which accomplishes the purpose of my invention is shown in Figs. 6 and 7 and in this case a helical spring 36 is arranged around the shifting rod 23 so as to bear at its front end against a screw 115 nut 25 on the shifting rod 23, while its rear end bears against a curved leaf spring 38 which latter is provided on its central part with an opening 37 which receives the shifting rod 23 while its opposite ends pass 120 through perforated ears 39 arranged on opposite sides of the rear end of the barrel. Upon screwing the nut 35 backwardly on the shifting rod 23 a tension is placed not only upon the helical spring 36, but also 125 upon the leaf spring 38, which latter during such tensioning operation slides rearwardly more or less in the perforated ears 39. The combined tension of these two springs operates to automatically move the plunger for- 130

- wardly and eject the material from the barrel when the valve forming the outlet at its front end is opened and the tension of the springs 36 and 38 is exhausted the same may 5 be retensioned for restoring the automatic operation of the apparatus by simply turning the screw nut 35 so as to move the same backwardly on the shifting rod 23 to the desired extent.
- 10 All of the several constructions of glazing apparatus herein referred to are very efficient in operation and capable of being easily manipulated and also quickly filled and put in operative condition so as to 15 facilitate the operation of glazing and reducing the cost of the same accordingly.

I claim as my invention:

1. A glazing apparatus comprising a barrel adapted to contain a charge of glazing 20 material and having an outlet at its front end, a valve for controlling said outlet, a plunger movable lengthwise in said barrel, a screw threaded shifting rod connected at its front end with said plunger, an adjusting 25 screw nut arranged on said shifting rod, and resilient means which receive the rearward thrust of said screw nut as the same moves away from the plunger and which are operatively supported from said 30 barrel.
2. A glazing apparatus comprising a barrel adapted to contain a charge of glazing material and having an outlet at its front end, a valve for controlling said outlet, a plunger movable lengthwise in said barrel, 35 a screw threaded shifting rod connected at its front end with said plunger, an adjusting screw nut arranged on said shifting rod, a spring bearing with its front end 40 against said nut and adapted to be flexed upon moving said nut away from said plunger, and an abutment for the rear end of said spring operatively connected with said barrel.
- 45 3. A glazing apparatus comprising a barrel adapted to contain a charge of glazing material and having an outlet at its front end, a valve for controlling said outlet, a plunger movable lengthwise in said barrel, 50 a screw threaded shifting rod connected at its front end with said plunger, an adjust-

ing screw nut arranged on said shifting rod, a spring bearing with its front end against said nut and adapted to be flexed upon moving said nut away from said plunger, and 55 a yoke which is engaged by the rear end of said spring and which is connected with said barrel.

4. A glazing apparatus comprising a barrel adapted to contain a charge of glazing 60 material and having an outlet at its front end, a valve for controlling said outlet, a plunger movable lengthwise in said barrel, a screw threaded shifting rod connected at its front end with said plunger, an adjusting 65 screw nut arranged on said shifting rod, a spring bearing with its front end against said nut, and a yoke which is engaged by the rear end of said spring and which is pivoted on said barrel so as to be capable of 70 swinging laterally.

5. A glazing apparatus comprising a barrel adapted to contain a charge of glazing material and having an outlet at its front end, a valve for controlling said outlet, a 75 plunger movable lengthwise in said barrel, a screw threaded shifting rod connected at its front end with said plunger, an adjusting screw nut arranged on said shifting rod, a spring bearing with its front end against 80 said nut, and a yoke which is engaged by the rear end of said spring and which is detachably connected with said barrel.

6. A glazing apparatus comprising a barrel adapted to contain a charge of glazing 85 material and having an outlet at its front end, a valve for controlling said outlet, a plunger movable lengthwise in said barrel, a screw threaded shifting rod connected at its front end with said plunger, an adjusting 90 screw nut arranged on said shifting rod, two coupling pins arranged on opposite sides of said barrel, and a yoke having a cross bar which engages with the rear end of said spring and is provided with an opening which receives said shifting rod and 95 two arms projecting forwardly from opposite ends of said cross bar and each provided at its front end with a hook which engages pivotally and detachably with one of 100 said pins.
